COMBINATION CUP DISPENSER AND TOOTH- BRUSH HOLDER

Michael W. Carroll, 406 Oak St., Three Oaks Township,
Berrien County, Mich. 49128

Filed June 28, 1968, Ser. No. 12,538

Term of patent 14 years

Int. Cl. D6—01

U.S. Cl. D33—26

FIGURE 1 is a perspective view of a combination cup dispenser and toothbrush holder embodying my new design;

The broken line representation of a cup in FIGURE 1 is for purposes of illustration only.

I claim:

The ornamental design for a combination cup dispenser and toothbrush holder, as shown and described.
